UNITED STATES PATENT OFFICE.

HUGH McCABE, OF LAWRENCE, MASSACHUSETTS.

FLANGING MACHINE.

Application filed July 31, 1922. Serial No. 578,589.

To all whom it may concern:

Be it known that I, HUGH McCABE, a citizen of the United States, residing at Lawrence, in the county of Essex and State 5 of Massachusetts, have invented certain new and useful Improvements in Flanging Machines; and I do hereby declare the following to be a full, clear, and exact description of the invention, such as will enable others 10 skilled in the art to which it appertains to make and use the same.

The present invention relates to an improvement in flanging machines.

In the flanging machine of the McCabe 15 Patent No. 1,006,861, the clamp plate 3 is pressed up by the wedge 5 to clamp the work against the top clamp plate 6 to hold the work during the flanging operation. This clamp plate 3, it will be seen by reference to 20 such patent, was supported to resist the pressure of the bender by a shoulder on the front of the machine against which it took. With each thickness of metal plate to be operated upon by this machine, there is provided a 25 clamp plate corresponding to the clamp plate 3 of such a length that its edge opposed to the bender is at the proper distance therefrom when the bender is in lowermost position. Experience with machines of this 30 type has shown that operatives sometimes neglect to put in the proper plate suitable for the thickness of the sheet metal being operated upon. Thus, for example, if a plate 3, suitable for use with one-quarter inch 35 plate, was in the machine, and an operative were to put in a piece of half-inch plate and operate the machine, it is obvious that an enormous pressure will be exerted upon the edge of the plate 3, tending to force it away 40 from the bender. This strain has been found to be so great that the frames of the machine have been repeatedly broken. The remedy which seemed to be necessary to be applied was to increase the strength of the frame, 45 but obviously there are limits to which it is desirable to increase the strength of the frame because in flanging very heavy sheet metal such as three-quarter inch boiler plate to double thickness of the plate, or some 50 other such extent, might even break such a machine, as the power applied to the bender by the pneumatic piston which actuates it is very great.

The object of the present invention is to 55 provide the machine with a breaker piece adapted normally to support the plate 3

against the working pressures incident to flanging metal, but which, when such plate is subjected to the enormous stresses due to the introduction of a piece of boiler plate of 60 greater thickness than that for which the machine is arranged, will break, requiring no more than a trifling replacement of the broken piece in order to put the machine in condition for further use. To this end the 65 invention consists in the improvement hereinafter described and particularly defined in the claims.

In the accompanying drawing illustrating 70 the preferred form of the invention, Figure 1 is a fragmentary side elevation of a portion of a McCabe flanging machine, showing the main operative parts; and Fig. 2 is a plan of the frame and bottom clamp plate, showing the breaker pieces in position. 75

The illustrated embodiment of the invention is described as follows: The top clamp 1, the frame 2, and the bender 3, are or may be all constructed as in such patented machine, except as hereinafter mentioned. 80 The front end 4 of the frame is provided with the segment groove 5, which is adapted to receive the T-head slide of the segment 6 which carries the bender 3. The bottom clamp plate 7 is provided with a tongue 8, which extends into the narrow portion of the segment slot 5. It is provided with a recess 9, which receives the pin 10 by which it is prevented from accidental displacement from the machine. The wedge block 11 85 operates in the manner of said patent, to raise and press the clamp plate 7 against the sheet of metal 12 introduced into the machine. At the front end of the bottom clamp plate 7 there are provided two plate 90 supporting hardened steel wedge pieces 13, against which the front edge of the bottom clamp plate 7 engages. These wedge pieces 13 are machined to fit correspondingly machined recesses in the frame piece 4, and are 100 normally held in place by the screws 14. The angle of the wedge pieces 13 is such that for all ordinary pressures which the machine is intended to stand, the coefficient of friction between the wedge pieces and the frame 105 will be such as to prevent the sliding of the wedge pieces in their recesses on the frame by means of the comparatively light and frail screws 14. Thus, with a piece of metal to be flanged, such as is shown in Fig. 1, and 110 with the edge of the bottom clamp plate occupying the position shown with relation

to the bender, the pressure exerted by the bender upon the bottom clamp plate will be such as may be carried with safety by the wedge pieces and the screws. If, now, the 5 operative were to insert a piece of boiler plate in the machine, say an eighth of an inch thicker than that for which it was adjusted, and should attempt to form a flange thereon by operating the machine, it will 10 be obvious that when the parts attempted to assume the position shown in Fig. 1, an enormous longitudinal pressure would be exerted upon the bottom clamp plate 7, tending to slide it forward. This enormous 15 pressure would be sufficient to squeeze out the wedge pieces 13, shearing off the screws 14 without injury to the machine. By the simple removal of the screws and their replacement with new ones, the machine would 20 again be ready for work. The expense of replacing an entire frame, which is a casting of great weight ordinarily made of cast steel and requiring expensive machining would be saved.

25 I am aware that breaker pieces have been introduced in machinery to save expensive parts from injury owing to the introduction of excessive strains due to some inadvertence, but so far as I am informed, I am the 30 first to avail myself of the use of a wedge-shaped piece in a wedge-shaped recess which, by the coefficient of friction between the parts, will oppose all ordinary stresses to which it is subjected without movement, 35 but which, under excessive pressures, will be permitted to slide and shear off or break such slight holding means as may be required in addition for securing the wedge-shaped pieces from movement.

Viewed in its broader aspects, the invention 40 contemplates the employment of a wedge-shaped piece in a correspondingly shaped recess, lightly held in position by some device adapted to be broken under excessive strain. The invention consists in 45 opposing the working strains by the coefficient of friction between inclined faces lightly held in proper position.

Having thus described the invention, what 50 is claimed is:

1. A breaker piece for a machine having a flat face to receive the working pressure of a part thereon, and an opposed inclined face supported by another part of the machine correspondingly inclined, the angle of inclination of the faces being such that the coefficient of friction between the inclined faces will be substantially ample to resist the working strains of the machine, and slight means for holding the inclined piece 60 in position.
2. A flanging machine having, in combination, a clamp provided with a movable clamping member, and a stationary clamping member for clamping and holding the work to be operated upon, a bender, and means for moving it around the corner of the clamping plate to form a flange on the metal, a wedge piece having a straight face engaging the clamp plate, and an inclined face, a portion of the frame of the machine being provided with a correspondingly inclined face to receive and normally support the wedge piece, and light means for holding the wedge piece in position adapted to 70 be broken under excessive pressures.

HUGH McCABE.
